Filed Aug. 4, 1958, Ser. No. 752,953

1 Claim. (Cl. 29—229)

This invention relates to pliers of the type having pins adapted to engage holes in a split ring for expanding or contracting the ring, the split rings being required to be expanded to be removed from a groove in a shaft and to be contracted to be removed from a groove in the bore of a member, which pliers can be used both for expanding or contracting a spring ring by moving the handgrips of the pliers together. The invention has for its object pliers of the type set forth which can be used for either expanding or contracting a split ring and readily converted from one use to the other. A further object of the invention is a simple and robust construction.

Referring to the drawings:

Figure 1 is a face view of a pair of pliers constructed according to this invention.

Figure 2 is a side elevation of a portion of the pliers shown by Figure 1, and

Figure 3 is a portion of a lever detached.

According to a convenient embodiment of this invention, two levers 1 and 2 are pivoted together intermediate their ends and the handgrip portion 2a of one lever, outward from the pivot, is made separate and adapted to be fixed in either of two positions to the portion 2b of the lever having an operative jaw thereon and extending outwardly from the pivot 3 in relation to the handgrip of the other lever 1. The separate handgrip 2a has a close ended slot 4 therein which is engaged on the pivot pin 3 of the levers. The other part 2b of the lever, beyond the pivot pin 3, has a quadrant-shaped tail-piece 5 in the form of a quadrant and has two notches 6 therein at right angles to one another. The separate handgrip 2a has a projection 7 pressed therefrom to project from the inner face of the handgrip and such projection 7 is adapted to engage the notches 6 and by engaging the projection in one notch 6 the handle ends of the levers are angularly arranged as indicated by broken lines so that by pulling the handgrips together as indicated by arrows c a split ring can be contracted and when arranged in the other notch, the split ring can be expanded by pulling the hand-

2

grips together as indicated by arrow b. The pivot pin 3 for the levers can be stepped so that it can be riveted to form heads to hold the levers together, whilst leaving the handgrip part 2a free to slide thereon under a head on the pin 3. The levers on the operative side of the pivot have bent over portions 8 which lie at right angles to the handgrip ends, that is to say parallel to the pivot axis of the pin 3, so that the projections 8 on the ends of the levers are parallel whilst moving towards or from one another. With this arrangement, the engaging ends or pins 8a of the operative jaws of the pliers can easily be seen by the operator, which facilitates engaging the pins 8a in the holes in the split ring.

Having thus described the invention, what is claimed as new and desired to be secured by Letters Patent is:

Pliers having pins on the operative jaws for engaging a split retaining ring for expanding or contracting same, comprising two levers, a pivot pin on which the levers are mounted, each lever comprising a handgrip portion on one side of the pivot pin and an operative jaw portion on the other side, the ends of the operative jaw portions being bent outwardly at right angles and carrying said ring expanding pins, one lever having a separate operative jaw portion formed separately from a separate hand grip portion, and both said separate parts being mounted to pivot on said pivot pin, a quadrant shaped tail piece on said separate operative jaw portion, a close ended slot in the separate hand grip portion engaged on said pivot pin to permit of sliding movement, heads on said pivot pin for holding captive the parts engaged thereon, two notches in said quadrant shaped tail-piece of the separate operative jaw portion, and a projection on the separate hand grip portion which can be selectively engaged in or disengaged from either of said two notches by sliding and pivoting such separate handgrip portion on said pivot pin, the slots in the said quadrant tail piece being separated by an angle so that when said projection is engaged in one notch the separate hand grip lies on one side of the other hand grip and when engaged in the other notch it lies on the other side of said other hand grip, so that when the hand grips are moved towards one another, the operative jaws will be moved together in one position and away from one another in the other position.
